(57) **CLAIM**

The ornamental design for an ellipsoidal syringe barrel, as shown and described.

DESCRIPTION

FIG. 1 is a perspective view of the ellipsoidal syringe barrel; FIG. 2 is another perspective view of the ellipsoidal syringe barrel rotated 90° from the perspective view shown in FIG. 1;

FIG. 3 is a cross-sectional view thereof, taken along the line 3—3 of FIG. 6;

FIG. 4 is a cross-sectional view thereof, taken along the line 4—4 of FIG. 5;

FIG. 5 is a bottom plan view thereof; and, FIG. 6 is a top plan view thereof.
